SECTIONAL SLIDABLE SHELF

Enoch Swedman, St. Paul, Minn., assignor to
 Seeger Refrigerator Company, St. Paul, Minn.,
 a corporation of Minnesota

Application October 20, 1941, Serial No. 415,717

8 Claims. (Cl. 211—153)

This invention relates to a sectional slidable shelf for refrigerators. The shelf may be made of two or more sections which are linked together and which provide a shelf means in the refrigerator when the shelf is extended in a horizontal position.

A feature of the invention resides in providing a shelf for a refrigerator and similar cabinets which may be extended to full horizontal shelf position or which may be released and moved into other positions where the shelf has a lesser shelf area and when moved entirely out of operating position, the refrigerator compartment is entirely free of the shelf. Thus the space in the refrigerator using this shelf construction may have a complete horizontal shelf across the same or a partial shelf, or the shelf may be slid away, leaving the refrigerator compartment free of the shelf so that taller articles may be placed therein.

The shelf construction includes track means along the side edges of the shelf to guide the sliding movement thereof. The track means may be such as to provide a single sectional shelf or a double shelf track and construction may be provided. Thus one or more tracks for the shelves may be used as may be desired.

A further feature resides in providing a locking means for holding the shelf in an extended position where the entire shelving is disposed horizontally in the refrigerator compartment. The locking and adjusting means for the shelf also provides means for holding the shelf partly slid away with the remaining portion acting as a shelf and locked to provide a partial shelf when it is desired.

Where it is desired to provide a pair of slidable sectional shelves operating in the same plane, a double center track may be provided which is supported at the back and extends horizontally and centrally in the refrigerator compartment, which central track portion may be provided with an adjustable standard to support the front end of the track at the proper adjusted level in the refrigerator compartment. With this construction, the side tracks are supported along the side walls in the refrigerator and extend down the back. Thus a pair of sectional shelves may be employed which are independently adjustable into different positions in the refrigerator compartment.

The shelf sections may be made with a wire frame and wire bars welded or secured together to provide a strong rigid frame in each section of the shelf, and by means of lugs projecting

from the frame the shelf sections are guided along the tracks and may be locked in the various positions.

5 A further feature resides in providing a slidable shelf which may be moved out of shelf operating position in a downward direction within the refrigerator or cabinet to provide a larger space for taller articles in the refrigerator or cabinet when desired.

It is also a feature to provide a slidable shelf which may be made in a single rigid shelf member slidably supported in side and vertically extending tracks or may be made up of shelf link portions.

15 These features, together with other details and objects will be more fully and clearly herein-after set forth.

The drawings illustrate:

Figure 1 is a perspective view of an open refrigerator, showing this shelf construction employed therein.

Figure 2 is a plan view of one of the sectional shelves removed from the refrigerator and supporting track.

25 Figure 3 is an enlarged section on the line 3—3 of Figure 2.

Figure 4 is a perspective view of the sectional shelf.

30 Figure 5 is a section on the line 5—5 of Figures 2 and 4.

Figure 6 is a detail top view of the double track, showing one shelf removed from the same and a portion of the other adjacent shelf in the adjacent track section.

35 Figure 7 is a sectional detail in side elevation of the track portion illustrated in Figure 6.

Figure 8 is a sectional plan view transversely through the refrigerator, looking down on the 40 pair of slidable sectional shelves, one of which is partially receded.

Figure 9 is a vertical section of the refrigerator looking toward one side of the center double track approximately on the line 9—9 of Figure 8.

45 Figure 10 is an enlarged detail, partly in section, showing a plan view of the back portion of the double track and the manner in which the same is supported to the back wall of the refrigerator.

50 Figure 11 is a front detail, a part of which is broken away, of the double center track for supporting the inner sides of the shelf sections.

Figure 12 is an enlarged sectional detail on 55 the line 12—12 of Figure 8.

Figure 13 is a section on the line 13—13 of Figure 8.

Figure 14 is a detail side elevation of the supporting bracket for the rear portion of the double track, a plan view of which is illustrated in Figure 10.

Figure 15 is a section on the line 15—15 of Figure 8.

This invention pertains to a slidable sectional refrigerator shelf and the drawings illustrate a refrigerator A in which the shelf B is shown in extended operative position in the refrigerator compartment. The shelf B may be made of two or more sections 10 and 11, respectively, which are hingedly connected together by the links 12. The front section 10 of the shelf B is formed with a wire frame 13, the ends of which are connected to the front finishing strip 14. The strip 14 may be decorative on the outer face as illustrated in Figure 4, or formed in any suitable manner, but as illustrated, is of a flat nature and the ends of the wire 13 are welded to rigidly secure the same to the strip 14. The shelf section 10 is formed with a series of small shelf wires 15 which are welded to the frame wire 13 and to the front strip 14 as shown in Figures 2 and 4.

The rear shelf section 11 is formed with a peripheral wire frame member 16 which is continuous and the shelf wires 15 are welded or secured to the frame member. In each shelf section, the shelf wires 15 extend parallel to each other and thereby form a smooth wire shelf which may lie in a single plane when the sections 10 and 11 are extended in the refrigerator as illustrated in Figure 1. The shelf may also be of full width to extend horizontally across the refrigerating compartment or the cabinet in which the shelf is placed.

The shelf sections 10 and 11 are adapted to be slidably supported by a track which is made up of a pair of parallel channels. The outer channel 17 of the shelf track is secured to the inside wall 18 of the refrigerator and the track is formed with a horizontal portion extending along the wall 18 and a vertical portion which extends parallel with the back wall and is spaced therefrom. The inner side 19 of the shelf supporting track may be a single track channel or a double track channel, as is illustrated in the drawings.

When it is desired to provide a single slidable shelf B in the refrigerator A, the central track portion 19 is single, whereas when it is desired to provide a double slidable shelf arrangement where the shelves B are positioned in the same plane, then the central track 19 is double and supports the shelves as illustrated.

The rear wall 20 of the refrigerator compartment supports the inner track portions 19 spaced from said wall by means of the bracket 21. By spacing the vertical portions of the track members 17 and 19 spaced from the wall 20, a space into which the shelf B may slide is provided within the refrigerator compartment of the refrigerator A. Thus the shelf B may be slid into this space with the shelf extending vertically and out of the way in the refrigerator or food compartment of the refrigerator A as illustrated in dotted outline in Figure 9.

The horizontal portion of the inner track member 19 is supported by the adjustable standard 22. Thus the horizontal portion of the track section 19 may be readily adjusted into proper relation with the outer section or sections 17

which are secured to the walls 18 of the refrigerator.

The front section 10 of the shelf B is provided with lugs 23 which are welded to the under side of the wire frame 13 and project from the sides of the same so as to form track engaging members which engage in the channels of the track portions 17 and 19. Directly forward from the track lugs 23 track lugs 24 are welded to the wire frame portion 13 projecting from the sides of the frame wire and these lugs 24 are adapted to engage on top of the track portions 17 and 19. The track lugs 24 carry the weight of the shelf B on top of the track portions 17 and 19 as the shelf sections 10 and 11 are slid along the track and back into the vertical position adjacent the wall 20 of the refrigerator. Angle lugs 25 are secured to the frame wire 13 just back of the front strip 14. The angle lugs 25 when engaging in the recess 26 are moved back so that the horizontally extending portion 27 engages under one edge of the recess 26 of the track portions 17 and 19 to prevent the front end of the shelf section 10 from raising away from the track portions. When it is desired to move the shelf B from its extended position, it is only necessary to engage the front strip 14 and pull the whole shelf forward sufficiently to free the shoulder edge 27 in the recess 26, permitting the front end of the shelf to be lifted while engaging the member 14 and then the shelf B may be slid back into the position illustrated in Figure 8, where the shelf may be locked in operative position with only the front section 10 acting as a shelf, leaving an open space in the refrigerator in front of the shelf section 10; however, if it is desired, the entire shelf B may be slid back into the dotted position illustrated in Figure 9, where the whole shelf B will extend vertically adjacent the rear wall 20 of the refrigerator compartment.

The rear section 11 of the shelf B is provided with track lugs 28 which engage in the tracks 17 and 19 to hold the shelf portion 11.

While the drawings illustrate two sections for each shelf B, namely, 10 and 11, it will be apparent that as many sections as may be desired may be connected together by the links 12 which hingedly connect the sections 10 and 11 together so that the sections may slide in the track portions 17 and 19.

In operating the shelves B where a pair of shelves are employed as illustrated in Figures 1 and 9, sections of the shelf B may be slid back out of operating position by releasing the locking angle 25 as heretofore set forth, and positioning it in complementary openings 26' formed in the top of the trackways 17 and 19 back from the front end of the track. Recesses 30' are also provided in the track sections 17 and 19 for the ends of the front portions 14 when the shelf B is slid back so that only the front section 10, for example, is in shelf operating position. It will also be apparent that where a series of slidable shelves B are used, as illustrated in Figure 1 and as shown in the plan sectional view of Figure 8, either of the shelves B may be pushed back so that only a portion of the same is in shelf operating position, or both shelves may be pushed back in the tracks so that the shelves will extend vertically along the rear wall 20 of the refrigerator compartment.

The idea of this slidable sectional shelf resides mainly in providing a shelf construction in a refrigerator which does not necessarily have to

be removed but which can be pushed back out of the way entirely, or a portion of the same moved back, to provide a larger space in the refrigerator for larger and taller articles than will fit under the shelf, without the shelf interfering with the same, yet maintaining the shelf sections in readiness for use at any time.

It is also apparent that the slidable shelves B may be removed entirely from the track portions 17 and 19 if it is desired, by releasing the lugs through the openings 26, 26' and 30. The shelves B are readily slidable to fully extend the same as illustrated in Figures 1 and 8. When the shelves are extended they are in locked position by the engagement of the angle lugs 25 in the slots 26. To unlock the shelves, the front bar 14 is engaged and the entire shelf B is pulled forward until the angle members 25 are in released position below the notches or slots 26. Then the front end of the shelf B may be raised to lift the angle lugs 25 out of the track and permit the same to slide along the top of the track until the shelf is in the desired position, registering with the notches 26' and 30, whereupon, the shelf can be locked in this position which would give half the shelf space to the shelf B as the front section 10 would be in shelf operating position. Therefore, this slidable sectional shelf construction may readily be positioned within the ordinary refrigerator compartment supported by the track portions so that the shelf will operate for more or less shelf space as the case may require.

In accordance with the patent statutes, I have described the principles, operation, and construction of my invention; and while I have endeavored to set forth the best embodiments thereof, I desire to have it understood that these are only suggestive of a means of carrying out my invention, and that obvious changes may be made within the scope of the following claims without departing from the spirit of my invention.

I claim:

1. A shelf for refrigerators and the like, comprising a series of rigid shelf sections hinged together, a channel-shaped track for the sides of said shelf having horizontal and vertical portions extending within the refrigerator compartment, openings formed leading into said track, lugs projecting from the sides of the front shelf sections and adapted to enter through said openings in said track to removably support said shelf on said track, lug means projecting from the sides of the rear shelf sections and engaging said track, and means for locking said shelf in different positions in said track.

2. A slidable removable shelf for refrigerators including a series of rectangular shelf sections, each of which is formed by an endless peripheral wire frame, and a series of shelf wires parallelly disposed and rigidly secured to said wire frame, means hingedly connecting said sections together to form a complete shelf, track means for holding said shelf slidably positioned within a refrigerator compartment, said track including a pair of parallelly extending channels, lug means projecting from said frames of said sections and engaging in said track portions, and lug means projecting from the front shelf sections engaging on top of said track means, said track means having a horizontal portion adapted to support said shelf in a horizontal position and a vertical portion in close proximity to a vertical wall of the refrigerator compartment but spaced therefrom, whereby said shelf may be slid into a ver-

tical position between the wall of the refrigerator compartment and said vertical portion of said track.

3. A sectional slidable shelf for refrigerators including shelf sections hingedly connected together, each section being formed with an endless wire peripheral frame, a series of shelf wires parallelly disposed and having their ends welded to said frame portion, the front section of said shelf being formed with a flat finishing strip to form the front edge of each shelf proper, track means for slidably supporting said shelf sections, lug means projecting from said shelf sections adapted to slidably engage said track means, said track means having portions fixed to the side walls of the refrigerator compartment, a double center track portion, an adjustable standard for supporting the forward end of the horizontal portion of said double track portion, vertical portions formed in the side track portions and said double center track portion, means for supporting said vertically extending portion of said double track portion spaced from the rear wall of the refrigerator compartment, and means for slidably positioning said shelf sections in said track portions, whereby said shelf portions may be fully extended or any of said shelf sections may be moved out of operating position and extending parallel with the inner wall of the refrigerator.

4. A sectional slidable shelf for refrigerators, said shelf being made in sections which are hingedly connected together, channel-shaped track means for slidably supporting said shelf sections, lug means projecting from said shelf sections adapted to slidably engage said track means, horizontal and vertical portions formed in said track means, said vertical portions of said track being spaced from the inner wall of a refrigerator to provide a space for the shelf to slide between the track and the wall when the shelf is moved out of operating position, said track means having openings to receive said lug means, and means for locking said shelf sections in different adjusted positions in said track means, said shelf sections being removably supported by said track means.

5. A slidable shelf for refrigerators including a pair of shelf sections hingedly connected together, each section forming a rigid shelf when extended, lug means projecting from the side edges of said shelf sections, a channel-shaped track, said lug means slidably engaging in and on top of said track to slidably support said shelf in a refrigerator in a manner to hold said shelf sections in horizontal position and slidable into a vertical position a section at a time, openings leading into said track means for said lug means to removably support said shelf on said track, and a finishing strip across the front section of said shelf adapted to act as a shoulder for engagement with the front end of said track to lock said shelf in fully extended position.

6. A slidable shelf for refrigerators including a pair of shelf sections hingedly connected together, each section forming a rigid shelf when extended, lug means projecting from the side edges of said shelf sections, a channel-shaped track, said lug means slidably engaging in and on top of said track to slidably support said shelf in a refrigerator in a manner to hold said shelf sections in horizontal position and slidable into a vertical position, a section at a time, openings leading into said track means for said lug means to removably support said shelf on said track, a

finishing strip across the front section of said shelf adapted to act as a shoulder for engagement with the front end of said track to lock said shelf in fully extended position, and locking means formed by some of the openings in said track which form a recess for the ends of said finishing strip when the shelf is moved to a partially extended position.

7. A slideable shelf for cabinets having inner walls including a pair of shelf hingedly connected sections, lug means projecting from the sides of said shelf sections adapted to slidably support said shelf, channel-shaped track means for receiving said projecting lugs on said shelf, some of said lugs projecting in and some on top of said track means, openings into said track means for releasably admitting the lugs of said shelf, portions of said track extending horizontally in the cabinet and portions extending parallel to the wall of the cabinet to support said shelf either in a horizontal position or in prac-

tically a vertical position with the wall of the cabinet.

8. A shelf for cabinets having inner walls, a series of shelf hingedly connected sections, means projecting from the sides of said shelf sections adapted to slidably support said shelf, channel-shaped track means for receiving said projecting lug means on said shelf, said lugs projecting in and some on top of said track means, openings into said track means for releasably admitting the lugs of said shelf, portions of said track extending horizontally in the cabinet and portions extending parallel to the wall of the cabinet to support said shelf either in a horizontal position or in practically a vertical position with the wall of the cabinet, and means in said track for locking said shelf sections in horizontal, and partially withdrawn positions.

ENOCH SWEDMAN.
